UNITED STATES PATENT OFFICE

2,547,662

FEED-BACK CIRCUIT

Theodore A. Rich and John E. Bigelow, Schenectady, N. Y., assignors to General Electric Company, a corporation of New York

Application April 26, 1949, Serial No. 89,676

2 Claims. (Cl. 250—209)

1

Our invention relates to amplifying devices, and has as its principal object to provide a new and improved feedback arrangement, whereby a gradual reduction in amplifier gain may be effected with increase in the frequency of an input signal impressed upon the amplifier, without accompanying excessive phase shift between the input signal and the amplified output signal corresponding thereto, which may produce oscillatory conditions in a system, such as a closed-cycle servo-system, wherein such an amplifier may be employed.

Our invention has found particular application in servo-systems of the type employing light beams to provide normal closed-cycle feedback. Such a light beam, when made responsive to the output signal of an amplifier, may be made to vary the impedances of photosensitive electron discharge devices connected in the input circuit of the amplifier. In the broadest aspect of our invention, an electrical feedback signal responsive to the output voltage of an amplifier, and supplementary to a light beam or other type of normal feedback which may be employed, is impressed in a series relation upon the input circuit of the amplifier to modify the response characteristics thereof.

Other objects and advantages of our invention will become apparent from a consideration of the following description when taken in connection with the figures of the accompanying drawing, wherein Fig. 1 is a schematic diagram of a preferred embodiment of our invention, including a feedback arrangement; Fig. 2 is a simplified equivalent circuit diagram of the arrangement of Fig. 1, but with feedback omitted; Fig. 3 is an equivalent circuit diagram of the arrangement of Fig. 2 with feedback added; and Fig. 4 is a graphical representation of certain operating characteristics of the arrangements of Figs. 2 and 3.

Referring now to Fig. 1, there is shown a closed-cycle servo-system arranged to provide an output voltage e_o substantially equal in magnitude to an unknown signal voltage e_o' . The servo-system shown comprises, generally, an amplifier 1 having an input circuit 2 and an output circuit 3, a detector 4, a light source 5, and an indicating element 6. Amplifier 1 includes an electron discharge device 7 having a cathode 8, an anode 9, and a control electrode 10. The potential required by electron discharge device 7 may be provided by a source of potential such as a battery 11. The positive terminal 12 of battery 11 is connected to anode 9 through a current-

2

limiting resistor 13, and a tap 14 of battery 11, negative with respect to point 12, is connected to cathode 8.

Input circuit 2 includes a pair of photosensitive electron discharge devices 15 and 16, having anodes 17 and 18 and cathodes 19 and 20, respectively. Cathode 19 of electron discharge device 15 is connected to anode 18 of device 16, and the common point therebetween is connected to control electrode 10 of electron discharge device 7. Anode 17 is connected through a current-limiting resistor 21 to a point 22 of battery 11, which is negative with respect to point 12. Cathode 20 is connected through a feedback resistor 23, designated as R_s , to a point 24 of battery 11, which is negative with respect to point 14.

It will be understood that this input circuit 2 is formed by photosensitive devices 15 and 16, resistors 21 and 23, and the portion of battery 11 between points 22 and 24, and that the potential of battery 11 tends to force a current through this circuit. The magnitude of such a current is dependent upon the impedances of photosensitive devices 15 and 16, as determined by the amount 25 of light falling thereupon, as will be understood by those skilled in the art. Thus, the potential of control electrode 10 with respect to cathode 8 is dependent on the relative amounts of light falling on photosensitive devices 15 and 16. As the potential of control electrode 10 is varied with respect to cathode 8, the potential of anode 9 being fixed with respect to cathode 8, the output voltage e_o across terminals 24 and 25 of amplifier 1 is likewise varied. The magnitude of voltage e_o may be indicated by indicator 6 which is connected across terminals 25 and 24.

Detector 4 may be a galvanometer having a moving element 27 biased to the center of its travel by a torsional spring 28, and having a mirror 29 affixed thereto. One terminal of detector 4 is connected to output terminal 25 of amplifier 1, while the other terminal of detector 4 is connected to one terminal of unknown voltage e_o' , designated as point 30. The other terminal of voltage e_o' is connected to the other output terminal 24 of amplifier 1. Thus, in effect, detector 4 is made to sense the difference or error between voltages e_o' and e_o which may be represented as $(e_o' - e_o)$. If these voltages are equal in magnitude the net voltages impressed on detector 4 is zero, and moving element 27 is undeflected. If e_o is greater than e_o' moving element 27 will be caused to move in one direction while if e_o' is greater than e_o moving element 7 will be caused to move in the opposite direction.

In the system as thus far described, there is no feedback interconnection between the input circuit 2 of amplifier 1 and the voltage impressed on detector 4. Such an interconnection is provided by a light beam 31 originating at light source 5 and reflected by mirror 29, and arranged to fall on photosensitive devices 15 and 16. Light source 5 comprises a lamp 32 and a source of potential such as a battery 33.

As previously noted, voltage e_o is dependent on the relative amounts of light falling on photosensitive electron discharge devices 15 and 16, which in turn is dependent on the position of mirror 29 and moving element 21 of detector 4.

The function of the servo-system as herein represented and described, is to provide an output voltage e_o in the servo-system approximately equal to the signal voltage e_o impressed on the servo-system. However, voltages e_o' and e_o are generally not exactly equal, but are unequal by the amount of error ($e_o' - e_o$) required by detector 4 to deflect mirror 29 by an amount sufficient to cause amplifier 1 to provide the required value of voltage e_o to produce a condition of equilibrium. A servo-system of the type described is well known in the art and does not of itself constitute a part of our invention. It will be understood that the embodiment herein represented is included to assist in the understanding of our invention which will be presently described.

While no reference has been made to the frequency of signal voltage e_o' , it is assumed that the frequency thereof may vary over a considerable frequency range. Accordingly, voltage e_o likewise varies in frequency with e_o' , but due to time lags in the various elements of the servo-system, as for example in the motion of moving element 29, voltages e_o and e_o' may be considerably displaced in phase with respect to each other. Furthermore, as is well known, the gain of the servo-system, represented as $e_o/(e_o - e_o')$, decreases, due to various factors, as the frequency impressed on the system is increased. As is well known, if the phase shift of voltages e_o and e_o' reaches 180° before the system gain is reduced to unity, an oscillatory condition may be established in the servo-system which, in general, is highly undesirable.

To bring about gradual reduction in system gain without excessive phase shift, we provide a feedback arrangement wherein a feedback signal is connected in series with photosensitive devices 15 and 16. Such a signal is provided by connecting the output voltage e_o of amplifier 1 across resistance 23 (R_2) through a coupling capacitance 34, designated as C_2 . Additional feedback may be provided by impressing voltage e_o across the combination of resistance 23 and photosensitive devices 15 and 16, through a coupling capacitance 35, designated as C_2' . Since photosensitive devices 15 and 16 have effective resistance and capacitance R_1 and C_1 respectively, voltage e_o in effect is impressed across a total resistance ($R_1 + R_2$) through capacitance C_2' . The effect of feedback of the type described will be explained more fully hereinafter in simplified equivalent arrangements.

Referring now to Fig. 2, there is shown in block form an amplifier 1, having an amplifying constant K , which may be considered as an equivalent of amplifier 1 in Fig. 1. Amplifier 1 is provided with an input circuit 2 and an output circuit 3. Input circuit 2 has an inherent effective capacitance C_3 represented by capacitance 36.

The resistance and capacitance of devices associated with input circuit 2, such as photosensitive electron discharge devices 15 and 16 in Fig. 1, are represented in Fig. 2 by a resistance 37, designated as R_1 , connected in series with input circuit 2, and a capacitance 38, designated as C_1 , connected in parallel with input circuit 2 and also in parallel with capacitance 36. The input voltage impressed on input circuit 2 is represented as e_s and corresponds to the voltage e_s in Fig. 1 which is impressed across control electrode 10 and point 24 in the input circuit of amplifier 1.

In Fig. 2, output circuit 3 is represented as providing output voltage e_o . It will be noted that in the arrangement of Fig. 2, no feedback is provided between e_o and e_s . In other words, the arrangement shown represents only a simple amplifier provided with an input voltage e_s and having an output voltage e_o .

Referring now to Fig. 3, an arrangement similar to Fig. 2 is shown, but with the addition of a feedback circuit 39. Feedback circuit 39 is provided with a feedback constant selector 40 having a feedback constant L . Output voltage e_o is impressed on selector 40 and a voltage e_oL is in turn impressed through a blocking capacitance 34, designated as C_2 , on a feedback resistor 23, designated as R_2 , connected in series with input circuit 2 between capacitance C_1 and C_3 . The arrangement of Fig. 3 is equivalent to the arrangement of Fig. 1, except that it does not represent a closed-cycle servo-system, but represents only amplifier 1, input circuit 2, and output circuit 3, and a feedback arrangement of the type shown in Fig. 1 interposed between the output and input circuits.

In Fig. 4, there are shown certain characteristics of the arrangements of Figs. 2 and 3. In particular, amplifier gain, represented by (e_o/e_s) , in particular, amplifier gain, represented by (e_o/e_s) is plotted against the frequency f of input voltage e_s . It is assumed that the typical values given in the following table have been assigned to the constants of Figs. 2 and 3.

$K = -12$ $R_1 = 30 \times 10^6$ ohms $C_1 = 5 \times 10^{-12}$ farads
 $L = \frac{1}{2}$ $R_2 = 2 \times 10^6$ ohms $C_2 = .01 \times 10^{-6}$ farads
 $C_3 = 50 \times 10^{-12}$ farads

In Fig. 4, curve 41 represents the approximate characteristic of amplifier 1 without the use of feedback, as represented in Fig. 2, while curve 42 represents the approximate characteristic of amplifier 1 with the addition of feedback, as represented in Fig. 3. It will be noted by reference to curve 41, that with increasing frequency f of input voltage e_s , the gain of amplifier 1 without feedback tends to remain constant over a considerable range of frequency and steadily decreases beyond a critical value of frequency, indicated as point 43 on curve 41. If feedback is included, however, the gain of amplifier 1 is initially constant over a fairly considerable range but has an initial decrease beginning at a substantially lower value of frequency, indicated as point 44 on curve 42, than is the case without feedback. The initial decrease of gain continues until point 45 on curve 42 is reached, after which the gain once again becomes constant over a fairly considerable range and ultimately decreases at point 46 in a manner similar to the decrease without feedback. It will be understood that for convenience curves 41 and 42 are approximate representations of the characteristics of amplifier 1 and that while points 43-46 inclusive conveniently represent intersections of the relatively

straight portions of curves 41 and 42, in reality the transitions between such portions are gradual and not definite intersections as indicated in Fig. 1.

The shape of curve 42 may be explained as follows: In the region between points 45 and 46, the negative feedback operates to reduce the amplification of the system, and therefore curve 42 lies substantially below curve 41. At lower frequencies, the amount of feedback is reduced by the increased impedance at low frequencies of capacitor 34 relative to the impedance of resistor 23. At frequencies below point 44, the impedance of capacitor 34 is so great relative to that of resistor 23 that the feedback is negligible, and the full amplifier gain is obtained. Thus the negative feedback is inoperative to reduce the amplifier gain at very low frequencies, and becomes effective to reduce the gain at higher frequencies, thus preventing oscillations. The frequency range at which the feedback becomes effective depends upon the time constant of capacitor 34 and resistor 23, and can be made to have desired values by proper choice of the capacitance and resistance values.

We have found a frequency response characteristic of the type represented by curve 42 of Fig. 4 to be particularly useful when employed in conjunction with servo-systems of the type embodied in Fig. 1. We have found that by making use of the feedback arrangement of our invention to provide a reduction of amplifier and servo-system gain with increasing frequency of a signal impressed upon the servo-system, without introduction of accompanying excessive phase shift therein, the prevention of undesirable oscillatory conditions in the servo-system is materially facilitated. Accordingly, in a stable servo-system, use of the feedback arrangement of our invention permits higher gains to be employed in the low frequency range than would otherwise be the case, without impairing stability in the high frequency range and with accompanying improved performance characteristics.

While we have shown a preferred embodiment and application of our invention, including a particular system of connections, it will be obvious to those skilled in the art that our invention may well take other forms and may be employed in other applications. We, therefore, aim in the appended claims to cover all such modifications as fall within the true spirit and scope of our invention.

What we claim as new and desire to secure by Letters Patent of the United States is:

1. In a closed-cycle photoelectric servo system, the combination of a direct coupled amplifier having input and output terminals, an electron discharge device having an anode and a photosensitive cathode, a resistor connected in series with said discharge device across said input terminals, and a capacitor connected in series with said resistor across said output terminals, whereby negative feedback voltage is applied across said resistor at frequencies above a value determined by the time constant of said resistor and capacitor, thereby preventing oscillation of the system.
2. A closed-cycle photoelectric servo system, comprising first and second electron discharge devices each having an anode and a photosensitive cathode, the cathode of said first device being connected to the anode of said second device, a resistor connected to the cathode of said second device, means to apply direct voltage across said first and second devices and said resistor in series, a third electron discharge device having an anode, a control electrode, and a cathode, said control electrode being directly connected to the circuit junction between said first and second devices, a mirror galvanometer connected to the anode of said third device, a light source, said galvanometer and light source being arranged to illuminate the photosensitive cathodes of said first and second devices by different relative amounts upon rotation of the galvanometer mirror, and a capacitor connected between the anode of said third device and the circuit junction between said second device and said resistor, whereby negative feedback voltage is applied across said resistor at frequencies above a value determined by the time constant of said resistor and capacitor, thereby preventing oscillation of the system.
